UNITED STATES PATENT OFFICE

FRANK S. NAWROCKI, OF NORTH HOLLYWOOD, CALIFORNIA

VEHICLE SIGNAL

Application filed May 20, 1932. Serial No. 612,487.

This invention relates to signal means for indicating changes of direction in the course of a self-propelled vehicle.

An object of the invention is to provide a signal of the character stated which may readily be attached to various makes of vehicles now on the market, and which is provided with an adjustable operating connection so that the variation of position, with reference to the steering wheel on different makes of cars, will not interfere with the efficient operation of the device.

Another object of the invention is to provide an improved mechanical movement for the control of a plurality of signal elements so that such signal elements may be timed for individual operation in such a manner that there will be no confusion between the signals nor failure to actuate the individual signals at the time required.

Although the signal device provided by this invention is primarily intended to be operated automatically by the steering mechanism of the vehicle yet the construction of the device is such that, if desired, it may be adapted for manual operation by the driver.

Other objects, advantages and features of the invention may hereinafter appear.

Referring to the accompanying drawings which illustrate what is at present deemed to be a preferred embodiment of the invention,

Fig. 1 is an elevation of the attachment looking at the obverse side of the face plate.

Fig. 2 is a cross section on line 2—2 of Fig. 1.

Fig. 3 is an elevation of the attachment looking at the reverse side of the face plate, the rear wall of the casing being broken away to avoid concealing interior parts.

Fig. 4 is a transverse section on line 4—4 of Fig. 2.

Fig. 5 is a somewhat diagrammatic view illustrating in a general plan the operation of the device.

Referring in detail to the drawings, the frame work of the device includes a transversely extending base plate 7 which is housed within a hemispherical casing 8 the

otherwise open side of which casing is closed by the upstanding face plate 9, except that said base plate is provided with a sight opening 10, said sight opening defining the signal display field. The base plate 7 is of an elongated character the length of said plate extending transversely of the vehicle upon which the device is mounted. The ends of said base plate are provided with upwardly directed portions 12 which form the end plates of the device, said end plates serving to support a pair of substantially parallel guide rods 13 and 14 which are mounted in vertically spaced relation to each other. Said guide rods serve to guide the movements of the signal elements 15 and 16 which are individually displayable one at a time through the sight opening 10.

Above the sight opening 10 the face plate is shown provided with a glass portion 10a and below said sight opening the face plate is shown provided with a glass portion 10b. These glass portions 10a and 10b are preferably both made of red glass. The lamps 10z located behind these glass portions serve to illuminate appropriate lettering carried by them. In the drawings the word "Stop" is shown inscribed upon the upper portion 10a and the word "Tail" is shown inscribed upon the lower glass portion 10b. As the face plate is viewed in Fig. 1, the letters TU are placed upon the imperforate opaque left hand portion of the face plate and the letters RN are placed on the corresponding opaque right hand portion thereof, the sight opening 10 being provided with a transparent glass covering 10c. Any well known means may be provided for holding the glass portions 10a, 10b and 10c in proper position, and therefore these portions of the device, though shown in the drawings, are not described in detail. Likewise the lamps 10z may be supported in any convenient manner as by the brackets 10y and the wiring for them arranged in any convenient way, an electric cord 10z being shown to supply the current.

Both of the signal elements are shown constructed according to the same pattern, and are each provided with an arrow-shaped in-

dicating portion 17 for displaying through the sight opening, said arrow-shaped portion forming one limb of an approximately horseshoe-shaped plate. The neck portion 5 19 of this plate connects the part 17 thereof with the other limb 20 of the plate, said limb 20 having at its free end a laterally directed portion 21 having therethrough an aperture through which loosely extends the rod 14. 10 The base of the neck portion of the horseshoe member which has been described is soldered or otherwise secured to a vertical bar or plate 22. The upper end of said plate 22 is provided with an aperture which 15 loosely receives the upper guide bar 13, and in the lower portion of said plate or bar 22 is an aperture which loosely receives the lower bar 14 and which is a companion to the aperture through the portion 21 already 20 referred to.

Means will next be described for operating, whether manually or from the steering and running gear of the vehicle, the signal elements 15 and 16. For this purpose there 25 is mounted upon the base plate 7 a guide plate 25 of an elongated character having at each of its long edges an upwardly and inwardly directed flange 26, thus providing a runway upon which is slidably mounted 30 an operating plate 27. Said guide plate is pivotally mounted between its ends, preferably somewhere near its mid-length, upon a pintle 28 which is supported by upwardly directed ears 25a with which the base plate 35 is provided.

The operating plate 27 is provided with a pair of cam slots 30 and 31 which are cut therethrough and which in a general way extend lengthwise of the plate. The slot 31 40 has a straight longitudinally extending left end portion 31a as viewed in Fig. 4 and at its other extremity said slot is provided with an outwardly directed portion 31b. Correspondingly the slot 30 is provided with a 45 straight longitudinally extending right end portion 30a and at its other extremity has an outwardly deflected portion 30b.

Part of the longitudinally extending portions 30a and 31a of the slots of the operating plate extend alongside of each other in 50 order that the two signal elements which are operated by these slots may ordinarily both be maintained in neutral or inoperative positions, that is to say there will be a neutral 55 zone provided wherein the steering wheel and front wheels of the vehicle may be deflected to a limited extent without operating the signal device to indicate a turn.

The operating plate 27 is slidably supported upon the guide plate 25 to reciprocate therealong, an operating rod 34 being secured to the mid-width of the end portion 60 of said operating plate, said guide plate being provided at its outer end with an upwardly directed portion 37 having there-

through an aperture through which slidably extends said operating rod.

As shown in Fig. 2 the convex portion of the casing is provided with a segmental slotted extension 40 through which extends the operating rod 34, a guiding tube 41 being provided for said rod to prevent buckling thereof during operation of the signals. In Fig. 2 the guiding tube 41 is shown located near the upper portion of the slotted extension 40, but it is to be understood that in practice it may be located at a lower point along said slotted extension, if the design of the vehicle makes a different adjustment necessary.

As shown in Fig. 5 the operating rod 34 is at its front end pivotally connected with the crank 41a which in turn is in fixed relation to the usual means for steering the front wheels 41b. The steering mechanism, 60 through the rod 34, controls and operates the signaling mechanism which has previously been described.

The operating plate 27 is operatively connected with the signal elements by means of two operating levers 50 and 51, which are swingingly mounted below the base plate 7. Each of said levers is pivotally attached to said plate 7 at the pivotal mounting 52 which is located near the rear end of each lever. The forward end of the lever 50 extends loosely through a short slot 20s in the lower ear 20a of the signal element 16, and other lever 51 is likewise at its forward end extended loosely through a 100 like slot 20s in the lower ear 20a of the other signal element 15. The slots through which the end portions of these levers extend are sufficiently long to permit a free swinging movement from the positions indicated in dotted lines in Fig. 4 to like positions at the opposite side of the mid-width of said figure.

At their other ends slightly beyond their 110 pivotal mountings each lever is provided with an upwardly directed curved extension 51a, these extensions respectively projecting upwardly through the slots 30 and 31 of the operating plate 27. The signal elements and operating rods and the slotted operating plate are thus related to each other in such a manner that one of the signal elements is projected into the sight opening from one end thereof while the other signal element remains stationary outside said 120 sight opening, and the other signal element can not be projected into the sight opening until the first mentioned element has been withdrawn therefrom. Means are therefore provided for singly projecting the signal 125 elements into the sight opening, it being possible for only one of said signal elements to occupy the sight opening at a time.

The upwardly directed extensions 51a of the levers 50 and 51 are each curved along 130

an arc concentric with the pintle or pivot pin 28 in order that the swinging adjustments of the guide plate about said pivot may not have any operative effect upon the 5 means for varying the position of the signal elements which are displayed through the sight opening of the face plate.

As shown in Figs. 1 and 3 the signal element 16 has the letter "L" mounted thereon 10 for display in the sight opening, and the signal element 15 has the letter "R" mounted thereon for display through the sight opening. It is to be understood that the complete word "Right" could be substituted 15 for the letter "R" to indicate a right hand turn or the complete word "Left" could be substituted for the letter "L" to indicate a left hand turn, but the letters "L" and "R" are shown as the preferred 20 means for indicating right and left hand turns. The letters TU and RN in the sides of the sight opening are of course arranged so that they spell the word "Turn" when viewed from the rear of the vehicle.

25 I claim:

1. In a vehicle signal, a frame defining a signal display field, a plurality of signal elements individually movable into said field to display a signal, an operating plate having cam slots therethrough, means for actuating said plate, and operating means for said signals, said operating means having portions engaging said slots.

2. In a signaling device for vehicles, an upstanding plate having a sight aperture therethrough, a frame to support said plate, a plurality of signal elements mounted upon said frame and individually displayable through said opening, guides for said signal elements along which they travel to and from signaling position, levers pivoted between their ends, said levers having their end portions at one side of said pivots operatively connected with said signal elements, an operating plate having cam slots therethrough with which the other end portions of said levers are operatively connected, means to slidably mount said guide plate upon said frame, and means to slide 45 said guide plate upon its said mounting to actuate the signals, the slots in said guide plate being constructed and arranged to bring said signal elements selectively and one at a time into view within said sight opening.

3. A signal operating device comprising a support, signal elements mounted thereon, a guide member of an elongated character pivotally mounted between its ends upon 50 said support, an operating plate having cam slots and mounted upon said guide plate to slide lengthwise thereof, signal operating elements consisting of rods having offset portions projecting through the slots of said 55 operating plate adjacent the pivotal mount-

ing thereof, said guide plate being tiltable upon its said mounting to various positions in all of which it remains in an operative relation to said rods, and means for slidably moving said operating plate to actuate 70 said rods and thereby operate said signal elements.

4. A signaling device comprising a support, a guiding means upon said support, a slide mounted to reciprocate along said guiding means, said slide having two slots therethrough the length of said slots extending in the same general direction as the direction of reciprocation of said slide, two signal operating elements one of which is 80 operatively related to one of said slots and the other of which is operatively related to the other of said slots, one of said slots being arranged to actuate the signal operating element which is operatively related 85 thereto during one portion of the movement of said slide and to maintain it stationary during the remaining portion of the movement of the slide while the other slot is arranged in a reverse relation to the signal 90 operating element which extends therethrough in order that one signal operating element be maintained inoperative while the other signal operating element is operated, and a signal proper operated by each of said 95 signal operating elements.

5. A signaling device comprising a support, a guiding means upon said support, a slide mounted to reciprocate along said guiding means, said slide having two slots 100 therethrough the length of said slots extending in the same general direction as the direction of reciprocation of said slide, two signal operating elements one of which is operatively related to one of said slots and 105 the other of which is operatively related to the other of said slots, each of said slots having one of its end portions substantially straight and in alignment with the direction of reciprocation of the slide and having its 110 opposite end portion deflected to act as a cam upon the signal operating element with which it is operatively related, the straight and deflected portions of one of said slots being reversely arranged to the corresponding portions of the other slot to provide for singly operating the signal elements.

6. A signaling device comprising a frame adapted to be attached to a vehicle to display a signal, said frame defining a signal 120 display field, two signals proper adapted for being singly displayed upon said field, guiding means extending across said field, said signals being mounted upon said guiding means to travel thereon to and from signaling position, each of said signals proper having an operating arm, and a reciprocatory member having two cam elements, one of said cam elements being operatively related to one of said arms and the other of 125 130

said cam elements being operatively related to the other arm, whereby said signals proper may be singly projected and withdrawn into said field from opposite sides thereof.

7. In a signaling device, a frame, a signal element movable to and from signaling position, a pair of substantially parallel rods mounted upon said frame, said signal element being slidably along said rods, said signal element comprising a part having an aperture therethrough, an operating lever projecting loosely through said aperture in a side-wise manner, and means for swinging said lever to operate said signal element.

8. In a signaling device, a frame comprising a plate having a sight opening therethrough, a pair of substantially parallel rods mounted upon said frame at the rear side of said sight opening, one of said rods being located adjacent one side of said sight opening and the other of said rods being located adjacent to the opposite side of said sight opening, two signal elements slidably mounted upon said rods, one of said elements being movable into said sight opening from one side thereof and the other of said elements being movable into said sight opening from the other side thereof, and operating means for said signal elements constructed and arranged to display them one at a time through said sight opening.

9. In a signaling device, a frame defining a signal display field, a pair of substantially parallel rods mounted adjacent to said field, a signal element consisting of a plate forming a signal proper displayable in said field, said plate having portions provided with apertures through which said rods extend in order to guide the movements of said signal element, and operating means to reciprocate said signal element upon said rods to and from signaling position.

10. In a signaling device, the combination with a frame defining a signal display field and a signal element movable into and out of said field; of operating means for said signal element, said operating means comprising an elongated guide plate mounted upon said frame, an operating plate positioned flat-wise upon said guide plate to reciprocate therealong, said guide plate having at one end a deflected portion having an aperture therethrough, an operating rod for operating said plate, said rod extending slidably through said aperture, said operating plate having a cam slot extending therethrough, and means for moving said signal element, said moving means being operatively related to said cam slot.

11. In a signaling device, a frame comprising a base plate, said frame defining a signal display field, a signal element displayable in said field, guiding means for said signal element mounted upon said frame and positioned to guide said signal element

while moving to and from signaling position, an operating plate having a cam slot therethrough, means to slidably support said operating plate at one side of said base plate to reciprocate transversely of said base plate, an operating lever pivotally mounted at the opposite side of said base plate, one portion of said operating lever being operatively connected with said signal element and another portion thereof extending through the slot of said operating plate to be actuated thereby, and means to reciprocate said operating plate.

12. In a signaling device for self-propelled vehicles, the combination with a support and two signal elements mounted thereon for movement to and from a signaling position, of a member having cam slots therein, means operatively relating one of said signal elements with one of said cam slots and the other of said signal elements with the other of said cam slots, and means operatively related to the steering mechanism of the vehicle to move said member back and forth to singly operate said signal elements, the operating means for said signal elements being related to said cam slots in such a manner as to provide a neutral zone for the operating means wherein slight turning movements of the vehicle will not effect an operation of either of said signal elements.

13. In a signaling device, the combination with a support and two signal elements mounted thereon for movement to and from a signaling position, of a member having cam elements therein, means operatively relating one of said signal elements with one of said cam elements and the other of said signal elements with the other of said cam elements, and means to move said member back and forth to singly operate said signal elements, the operating means for said signal elements being related to said cam elements in such a manner as to provide a neutral zone for the operating means wherein slight turning movements of the vehicle will not effect an operation of either of said signal elements.

14. In a signaling device, a support, a guiding means upon said support, a slide mounted to reciprocate lengthwise along said guiding means, said slide having two slots therethrough the length of said slots extending in the same general direction as the length of said slide, two signal operating elements one of which is operatively related to one of said slots and the other of which is operatively related to the other of said slots, each of said slots having one of its end portions substantially straight and in alignment with the length of the slide and direction of reciprocation thereof and having its opposite end portion deflected to act as a cam upon the signal operating element

- with which it is operatively related, the deflected portions of one of said slots being reversely arranged with relation to the corresponding deflected portion of the other slot to provide for singly operating the signal elements, said signal operating elements being related to the longitudinally extending portions of said slots in such a manner that a limited reciprocation of the slide does not project either signal element into the signal display field whereby a neutral zone is provided with relation to the operation of the two signals in order that neither signal be displayed by a slight turning movement of the vehicle, and means operatively connecting said slide with the steering means of the vehicle.
15. In a turn indicating device attachable to a vehicle, a frame having a signal display field, a signal element mounted upon said frame to move into and out of said field, a lever to actuate said signal element, a slide having a cam element which extends in a general way lengthwise of said slide, an elongated guide for said slide, said guide being pivotally supported between its ends and having a swinging adjustment upon said frame, the aforementioned lever being swingingly mounted between its ends upon a pivotal support, said lever having a curved portion which maintains an operative relation to the cam of said slide, said curved portion being curved along an arc substantially concentric with the pivotal mounting of said guide, and means operatively related to the steering mechanism of the vehicle to reciprocate said slide.
16. In a turn indicating device attachable to a vehicle, a frame having a signal display field, a signal element mounted upon said frame to move into and out of said field, a lever to actuate said signal element, a slide having a cam slot therethrough which extends in a general way lengthwise of said slide, an elongated guide for said slide, said guide being pivotally supported between its ends and having a swinging adjustment upon said frame, the aforementioned lever being swingingly mounted between its ends upon a pivotal support which extends at substantially a right angle to the pivotal support of said guide, said lever having a curved portion which at all times extends through said cam slot, said curved portion being curved along an arc substantially concentric with the pivotal mounting of said guide, and means operatively related to the steering mechanism of the vehicle to reciprocate said slide.
17. In a signaling device for vehicles, in combination, a signal element movable to and from a signaling position, means to operate said signal element, said operating means comprising a member having a slot consisting of two parts which meet each other at an angle, and a second member having a projection which enters said slot, means to connect one of said members with said signal element, and means to connect the other of said members with the steering mechanism of the vehicle, thereby to cause a relative movement of said projection and slotted member, the signal element remaining substantially stationary while said projection moves relatively to one part of said slot and being actuated by its relative movement along the other part of said slot.
